FINGER-HELD GARDENING CLIPPER

Albert H. Torongo, Jr., Yardley, and Frank W. Earnest III, Williamsport, Pa., assignors to Frank W. Earnest, Jr., doing business as Frank Earnest Company, Williamsport, Pa.

Filed July 11, 1966, Ser. No. 3,017

Term of patent 14 years

(Cl. D95—1)

FIG. 1

FIG. 3

FIG. 2

FIG. 4

FIG. 6

FIG. 5

FIG. 7

FIGURES 6 and 7 are respectively top and bottom plan views thereof.

We claim:

The ornamental design for a finger-held gardening clipper, as shown and described.
